(57) **CLAIM**

I claim the ornamental design for a compressor, as shown and described.

DESCRIPTION

FIG. 1 is a perspective view from front and left hand of a compressor according to the present invention;

FIG. 2 is a left side view of the compressor of FIG. 1;

FIG. 3 is a right side view of the compressor of FIG. 1;

FIG. 4 is a top view of the compressor of FIG. 1;

FIG. 5 is a bottom view of the compressor of FIG. 1;

FIG. 6 is a rear view of the compressor of FIG. 1; and,

FIG. 7 is a front view of the compressor of FIG. 1.

The broken lines shown in the figures are included for the purpose of illustrating portions of the compressor which form no part of the claimed design.
